DESIGN FOR AN INDICATING NOVELTY FOR A TOILET DOOR

Daniel Paul Iddings, San Francisco, Calif.

Application July 6, 1937, Serial No. 70,269

Term of patent 14 years

To all whom it may concern:

Be it known that I, Daniel Paul Iddings, a citizen of the United States, residing in the city and county of San Francisco and State of California, have invented a new, original, and ornamental Design for an Indicating Novelty for a Toilet Door, of which the following is a specification, reference being had to the accompanying drawing, forming part thereof, in which:

I claim:

The ornamental design for an indicating novelty for a toilet door, substantially as shown.

DANIEL PAUL IDDINGS.
